UNITED STATES PATENT OFFICE.

FERDINAND RUSTANT, OF MANILA, PHILIPPINE ISLANDS.

DESIGN FOR A POISON-BOTTLE.

53,614.

Specification for Design.

Patented July 15, 1919.

Application filed February 4, 1919. Serial No. 275,028. Term of patent 14 years.

To all whom it may concern:

Be it known that I, FERDINAND RUSTANT, a citizen of the United States, residing at Manila, in the Philippine Islands, have invented a new, original, and ornamental Design for a Poison-Bottle, of which the following is a specification, reference being had therein to the accompanying drawing, forming part thereof.

The figure is a view in side elevation of a poison bottle, showing my new design.

I claim:

The ornamental design for a poison bottle, as shown.

In testimony whereof I hereunto affix my signature.

FERDINAND RUSTANT.
